O. O. TERHUNE

COMBINED HOLDER AND COMB CLEANER

Filed Aug. 1, 1923

E. Q. Ruppert.

WITNESS:

O. O. Terhune
INVENTOR
BY Victor J. Evans

ATTORNEY

UNITED STATES PATENT OFFICE.

OTIS O. TERHUNE, OF GERING, NEBRASKA.

COMBINED HOLDER AND COMB CLEANER.

Application filed August 1, 1923. Serial No. 655,080.

To all whom it may concern:

Be it known that I, OTIS O. TERHUNE, a citizen of the United States, residing at Gering, in the county of Scotts Bluff and 5 State of Nebraska, have invented new and useful Improvements in Combined Holders and Comb Cleaners, of which the following is a specification.

This invention relates to a combined 10 holder and comb cleaner, the general object of the invention being to provide a block having a bunch of raveled rope or the like secured thereto to form a cleaner for combs and a strip forming a pocket to receive 15 combs and other articles.

This invention also consists in certain 20 other features of construction and in the combination and arrangement of the several parts, to be hereinafter fully described, illustrated in the accompanying drawings and specifically pointed out in the appended 25 claims.

In describing my invention in detail, reference will be had to the accompanying 30 drawings wherein like characters denote like or corresponding parts throughout the several views, and in which:—

Figure 1 is a front view of the invention.

Figure 2 is an edge view.

Figure 3 is a detail view.

As shown in these views the device is formed of a block 1 to which a strip 2 is fastened in such a manner as to provide a pocket to receive various articles such 35 as combs, hair pins and the like. Strands of rope or the like, shown at 3, are fastened to the bottom of the block under the bottom of the strip and these strands are unraveled so as to produce a bundle of small 40 threads which are adapted to pass between

the teeth of a comb to clean the same. The strands may be colored in any desired manner to add to the attractiveness of the device. The top of the block is provided with an eye 4 so that it can be suspended from 45 a nail on a wall or other support. The block may be provided with a mirror if desired. The comb is simply drawn through the unraveled rope or other material and as the threads pass between the teeth they will 50 remove all dirt therefrom. The ends of the rope which are fastened to the block are hidden from view by the strip which forms the pocket.

It is thought from the foregoing description that the advantages and novel features of my invention will be readily apparent. I desire it to be understood that I may make changes in the construction and in the combination and arrangement of the several parts, provided that such changes fall 55 within the scope of the appended claims.

What I claim is:—

1. A device of the class described comprising a support, a pocket formed thereon and a bundle of thread-like material connected with the lower end of the support and depending therefrom to form a comb 65 cleaner.

2. A device of the class described comprising a block, strands of rope connected with the lower end of the block and unraveled to form a comb cleaner and a strip connected with the edges of the block and spaced from the block to form a pocket, the 70 strip covering the ends of the rope which are fastened to the block.

In testimony whereof I affix my signature.

OTIS O. TERHUNE.
